UNITED STATES PATENT OFFICE.

WILLIAM H. DERBYSHIRE, OF CHAMBERSBURG, PENNSYLVANIA.

DESIGN FOR A FRAME FOR HYDRAULIC RIVETERS.

SPECIFICATION forming part of **Design No. 30,997**, dated **June 13, 1899**.

Application filed **May 18, 1899**. Serial No. **717,367**. Term of patent **14 years**.

To all whom it may concern:

Be it known that I, WILLIAM H. DERBYSHIRE, a citizen of the United States, and a resident of Chambersburg, Pennsylvania, have invented and produced a new and useful Design for a Frame for Hydraulic Riveters, of which the following is a specification.

My design for the frame of a hydraulic riveter is clearly illustrated in the accompanying drawings, in which—

Figure 1 is a side view of the frame, and Fig. 2 is a plan view.

The essential feature of the design is the yoke-frame having on one arm a single extension and on the other arm a double extension.

A is the frame, made in the form of a yoke,

having a narrow tapered arm *a* and a wide tapered arm *a'*, forming a throat *c*. At the upper end of the arm *a'* are two extensions *b* ²⁰ and *d*. The portion *d* extends beyond the portion *b*, and a throat *c'* is formed between the two extensions.

I claim—

The design for the frame of a hydraulic riveter as herein described and as shown in the accompanying drawings.

In testimony whereof I have signed my name to this specification in the presence of two subscribing witnesses.

WILLIAM H. DERBYSHIRE.

Witnesses:

J. NEVIN POMEROY,
JAMES A. SMITH.
